METHOD OF AND APPARATUS FOR
TRANSPORTING GOODS

Charles A. Nelson, Albany, N. Y.

Application February 21, 1933, Serial No. 657,851

10 Claims. (Cl. 105—159)

The present invention relates to a new and improved method for the transportation of goods, and to apparatus by means of which the improved method can be conveniently and economically practiced.

A very considerable proportion of the traffic in goods and passengers, formerly transported over railways, or jointly over railways and highways, now passes over highways exclusively, especially where the passengers or goods are to be transported through relatively short or intermediate distances. The gradual taking over by the bus and truck lines of such a considerable portion of the passenger and freight traffic of the country has been brought about by numerous well known causes, which need not be here enumerated, but one principal advantage which the highway carrier has over the railway carrier consists in his ability to transport goods or passengers from any shipping point in one locality to any definite receiving point in a different locality, without trans-shipment of the goods or handling during transit in any manner. This method of transport, which is generally designated "door to door" transport, not only saves greatly in time of shipment over the mode of transportation which involves loading onto and unloading from railway cars at transfer points, but is less expensive to the shipper and in most cases insures that the goods will be received in better condition than when they pass over the railways. The increasing passenger and freight traffic on the public highways has, however, greatly increased the traffic hazard incident to ordinary highway travel, the buses, trucks, and trailers now commonly used being in many instances of such large size and great weight as to constitute objectionable traffic hazards, as well as being destructive to the highways.

The present invention contemplates the removal, so far as possible, of the heavy freight and passenger traffic from the highways and the restoration of such traffic to the railways, that is, the invention contemplates the conjoint use of both the highways and railways in effecting the transfer of goods or passengers, the advantage of "door to door" transfer being retained and also the further advantage of quick, safe, convenient, and economical transportation of the goods or passengers along the railways between relatively distant points. In other words, the invention contemplates a combination of the two rival transportation systems now in general use wherein the advantages of both are retained and

realized and the principal disadvantages of both avoided or lost.

It is well-known that railways throughout the country could carry many times the amount of traffic which now passes over them. Without making any changes or additions to the trackways or road bed structures, many more trains might be accommodated each day, the railway tracks now actually standing idle most of the time. Furthermore, the railways generally form the most direct routes between principal points, provide the easiest grades for traffic, avoid congested centers, and in general constitute instrumentalities for the safe, fast, and economical transportation of traffic of all kinds. In accordance with my invention, the railways are employed for the transportation of goods or passengers so far as is possible, and road vehicles are employed to enable the operator to accomplish the objects which cannot be accomplished by the railways and railway rolling stock alone, i. e., the removal of the goods from point of shipment to the nearest railway and subsequent removal of the goods or passengers from that point on the railway nearest the destination, to the actual destination.

In order to accomplish the stated objects, I provide a special type of road vehicle and a special type of rail vehicle, the road vehicle having in general the same construction as those now seen on the highways in large numbers but being provided with means whereby it, or a number of such vehicles, may be combined with a number of the special rail vehicles at a point of interchange to form a train of novel character, comprising alternately arranged rail and road vehicles, the road vehicles being elevated so as to be carried by the rail vehicles, with their road wheels in inoperative positions, which train may be transported through any desired distance and may be rapidly disassembled at a distant point of interchange, the road vehicles being detached from the rail vehicles, lowered, and again set upon the highway, after which they may be moved to any points of delivery originally intended. While, in order to practice the invention, it will be necessary to provide a number of rail vehicles of new type resembling trucks, but few changes to the present various well-known types of passenger and freight trucks or buses need be made and these changes may be conveniently and inexpensively effected.

Thus, to equip the well-known "semi-trailer" so that it may be included in a train for rail travel, it will be necessary to modify it only by

the addition of a second coupling device at the rear end thereof so that each end of the semi-trailer is provided with means for engagement with a rail vehicle, the semi-trailer as now constructed being already provided at its forward end with a coupling by means of which it may be readily coupled to or uncoupled from a tractor. In the case of full trailers, i. e., trailers having four road wheels, it will be necessary to add a coupling device at each end of the trailer body.

By the term "coupling device" as used above, is meant a mechanism which not only functions as a means for connecting two vehicles together for simultaneous movement but which also elevates one of the vehicles relatively to the other, so that part of the weight of the vehicle thus elevated is carried by the other vehicle so long as they remain coupled. There are a number of devices of this kind now in common use.

Where it is desired that all formal requirements of modern railway practice be complied with, the road and rail vehicles may be equipped with interlocking coupling devices of modified type, including standard railway type draft rigging which may tend to increase the margin of safety of a train built up of vehicles in the specified manner. It will be appreciated that the tractive effort of the prime mover, which may be at either end of the train and which may exert thereon either a pushing or pulling force, will pass through the frames of the road vehicles included in the train and that these vehicles and the means which couple them respectively to the several rail vehicles, should be strongly constructed so as to withstand the forces thus transmitted through them.

The first form of coupling device which I contemplate using is provided with means which permits interlocking and disengagement of the road and rail vehicles in the manner now practiced in effecting the coupling or uncoupling of the common tractor and semi-trailer. Such a means, for instance, which is generally called a "fifth wheel", is disclosed in the patent to Pescatore, No. 1,084,820, issued January 20, 1914. The coupling of one of the highway units, equipped with such devices, to two of the railway units may be effected by pushing the railway units beneath opposite ends of the highway unit, whereupon the highway unit is elevated to such extent that its road wheels completely clear the trackway, the ends of the highway vehicle riding up inclined planes on the rail vehicles in effecting this movement of bodily elevation. When it has been raised to such position, with its ends resting upon two of the rail vehicles and its supporting wheels elevated and inoperative, the locking means of the railway units or vehicles are active to cause such engagement of the ends of the road vehicle with the rail vehicles that these vehicles are locked together for transit over the railway road bed, the locking connections permitting pivotal movement of the vehicles relatively to each other as is necessary in the case of a continuous train of interconnected vehicles.

The invention may have various embodiments both in its method and apparatus aspects. Thus, while the method contemplates that in the usual case each of the road vehicles will be loaded with goods or passengers at a point remote from the railroad and will be unloaded at a point of discharge remote from the railroad, it is, of course, possible that the road vehicle may actually be loaded while mounted upon the supporting rail

vehicles and positioned on a side track and, furthermore, that the unloading operation may in certain instances be conducted without detaching the road vehicle from the associated rail vehicles if a side track is available at the destination point. The actual mechanism for carrying out the invention may be modified greatly to suit various operating conditions, and those forms which are illustrated in the accompanying drawings are set forth by way of example only.

In the drawings:

Figure 1 is a side elevation of a form of highway train comprising a tractor, a semi-trailer, and full trailer, the two trailing vehicles having been modified in accordance with the invention for subsequent assembly with rail vehicles;

Figure 2 is a side elevation of a railway train of alternate road and rail vehicles;

Figure 3 is a similar view of a similar train showing the modified type of coupling device for coupling the various units together;

Figure 4 is a top plan view of one of the rail vehicles or trucks;

Figure 5 is a side elevation of the same;

Figure 6 is an end view of the truck;

Figure 7 is a side elevation of one of the trucks or rail vehicles shown in Figure 3, the adjacent ends of two adjacent road vehicles supported thereon;

Figure 8 is a top plan view of one of the rail vehicles;

Figures 9 and 10 are two views of a detail; and

Figure 11 is a side elevation of the upper portion of one of the coupling devices.

Referring first to Figures 1, 2, and 3. A tractor is indicated at 10, this tractor comprising a body mounted upon wheels and adapted to be propelled by a gasoline engine or other like power plant, the body being provided at its rear end and approximately above its rear axle with the bottom portion of any suitable type of "fifth wheel" coupling device which is adapted to engage and interlock with the upper portion of a fifth wheel unit mounted upon the forward end of the semi-trailer, indicated generally at 11, approximately one third of the weight of the semi-trailer being transmitted to the tractor 10 by this connection. Essentially, the coupling device comprises a circular disc or plate either fixedly or pivotally mounted upon the forward end of the semi-trailer and underneath the frame thereof, this disc having a central pin projecting downwardly therefrom as shown in Figure 11. The bottom portion of the device is preferably constructed substantially as shown in Figures 4 and 5 of the drawings, such a mechanism being here illustrated as mounted upon the truck or rail vehicle. It comprises essentially two inclined guide plates 12, the upper surfaces of which are in a common inclined plane and the inner edges of which converge upwardly as shown in Figure 4, these inner edges 13 merging with parallel inner edges of a slot formed centrally in a disc-like plate 14, the upper surface of which is horizontal and which is mounted for limited axial sliding movement upon the parallel supporting rods 15, this axial movement being opposed by the coiled compression springs 16.

As is well known, a semi-trailer such as indicated at 11 normally rests, when disengaged from its tractor 10, upon the road wheels 17 and the smaller supporting wheels 17'. If it be desired to couple the tractor and the semi-trailer, the tractor is backed axially of the semi-trailer, and the central pin of the upper coupling unit is 75

guided by the inclined plate members 12 into the slot in the disc-like horizontal supporting member 14, whereupon an automatic locking member (not illustrated) locks the pin in such position. In this coupling movement the forward end of the semi-trailer is naturally lifted so that the supporting wheels 17 are disengaged from the ground or floor and, after the coupling has been accomplished, these supporting wheels may be further elevated, by well-known means, so as to be completely out of the way. Disengagement of tractor 10 and semi-trailer 11 may be effected by releasing the locking means which retains the central or king pin of the upper member of the coupling device, and the tractor then moved forwardly. The upper coupling member then slides down the inclined plates 12 and the two portions are wholly disengaged from each other.

As can be seen from Figure 1, the rear end of the semi-trailer 11 is likewise provided with an upper coupling member, this member comprising essentially the circular disc 18 and the central pin 19, both of which are more clearly illustrated in Figure 11. Likewise the full trailer 20, that is, the trailer having two complete axles and four wheels, is provided at each end, on the under side of its supporting frame members, with two similar upper coupling members, the purpose of which will be hereinafter more clearly explained. Ordinarily for highway travel the full trailer is connected either to the tractor 10 or to a semi-trailer such as 11 by means of a simple draw-bar such as indicated at 21.

The rail vehicle which I utilize in carrying out my improved method of transporting goods or passengers is shown in detail in Figures 4, 5, and 6 and comprises a frame, preferably having side frame members such as indicated at 31 suitably connected together by integral cross webs, these side frame members being provided with the usual pedestals for the reception of axle bearings and axles. In fact the truck may resemble to a considerable degree the ordinary and well-known four-wheel railway truck of common type. It is provided with springs 32 and breaking mechanism adapted to be either operated pneumatically or by hand wheels such as indicated at 33. The details of this braking mechanism need not be specifically described as any well-known form may be employed by means of which it is possible to either actuate the brakes by hand or by means of a valve located at a distant point. The brake shoes are indicated at B, the operating cylinder at C, the air reservoir at A, and triple valve at T. Upon the upper surface of the frame of the truck, and firmly and rigidly supported thereon, are two lower portions of coupling devices, facing in opposite directions as shown. Coupling mechanisms of any customary or usual type are secured to the ends of the frame of the rail vehicle, the opposed draw-bars of these mechanisms being indicated at 34 and 35 respectively. By means of these couplings a plurality of rail vehicles may be coupled together, or such a vehicle may be connected to other railway rolling stock, or to a highway vehicle in a manner hereinafter to be described.

In building up a train at an interchange point, a number of loaded road vehicles are assembled and are placed directly over a trackway at a point where the pavement level is approximately the same as that of the rail tread surfaces, as shown in Figure 6. Each such loaded vehicle is then assembled with two rail vehicles, one of which is moved under each end of the road

vehicle, elevating the same until the wheels of the road vehicle are suspended and inoperative and interlocking the road vehicle with both rail vehicles. This method of assembly is carried out whether the road vehicles be of the semi-trailer 5 or the full trailer type so that the train thus built up may have a number of both forms of trailers or still other forms of such vehicles if desired, it being only necessary to provide each vehicle which is to be assembled in the train with the 10 upper coupling unit of a coupling device, at each end thereof. Naturally also, the exact shape of the goods or passenger carrying body of the road vehicle is immaterial, and it may be a box body, a flat body having shipping containers mounted 15 thereon, or the like. After a train is fully assembled and the various coupling devices are securely interlocked, it may be drawn any distance over the railroad, the tractive effort of the prime mover being transmitted from each rail vehicle 20 to the following one through the intermediate road vehicle which they support.

If it be desired to so design the mechanism that the tractive effort of the locomotive or propelling vehicle, whatever its character, be transmitted from unit to unit of the train through standard railroad couplings, this can be arranged in the manner illustrated in Figures 3, 7, and 8 of the drawings. Here the road vehicles are provided with central bracket-like structures 40 which support draw-bars and coupling heads, the coupling heads being indicated at 41 and being positioned to interlock with the coupling heads of the trucks or rail vehicles when the road vehicles are properly positioned in the train. The 35 draft pull from rail vehicle to rail vehicle is therefore transmitted through standard coupling devices well able to withstand any of the shocks incident to traffic over the road bed.

When coupling devices such as have been just 40 described are utilized, it is necessary to modify somewhat the lower coupling portions, which are mounted upon the intermediate trucks or rail vehicles. Thus, the upper portion of each coupling must be allowed to swing or slide laterally 45 relatively to the lower portion as the angularity of the rail unit changes with respect to that of the road unit in the natural progress of the train around curves. To permit sufficient sliding movement of the upper portion of the fifth wheel assembly over the lower, the horizontal supporting plate of the lower portion is laterally extended as shown in Figure 8, and likewise the central slot within which the downwardly projecting king pin of the upper portion is received is extended 50 laterally in both directions from the center, as indicated at 42 in Figure 8. A flange indicated at 43, preferably integral with the edge of the supporting plate, limits the lateral sliding movement of the disc of the upper coupling unit so that the two portions cannot become disengaged or the upper portion moved so far over to the side of the rail unit as to tend to tip over the rail unit.

A flexible air hose swung from an air conduit mounted on the road vehicle is indicated at 44, a similar air hose mounted upon the truck or rail vehicle at 45, and air hose connections at 46. After the formation of a complete train of road 70 and rail vehicles in the manner previously described, all of the air couplings 46 are connected, and the braking mechanisms of the several rail units can be simultaneously operated from the cab of the locomotive, rail car, or other power 75

unit which is employed to move the train along the track.

Due to the fact that the road vehicles are elevated when assembled in the train and also due 5 to the fact that each of the load carrying axles of the road vehicles is spring-supported, it may be found that the axles and wheels will tend, in certain instances, to drop too far toward the railway road bed. In order to prevent such happening, straps such as indicated at 48 in Figures 9 10 and 10 may be passed around the axles of the road wheels and secured at their upper ends to the under frames of the respective vehicles. These straps prevent downward movement of the 15 axles more than a predetermined amount.

The method of goods or passenger transportation contemplated by the present invention has been previously explained, but a brief resume may be given. The semi-trailer, for instance, may be 20 loaded with goods at a store platform in a given city for transportation to a definite point in a distant city. It is sealed, transported to the nearest point of railway interchange, assembled into a train with a number of other road vehicles, and 25 the requisite number of railway trucks, transported over the railway right of way to the point nearest its ultimate destination, disassembled from the train, and then drawn by another tractor to the point where it is unloaded. The convenience and economy of the method will at once 30 be apparent. No handling of the freight intermediate its points of shipment and destination is necessary, the expensive hauling over the highway for a long distance is avoided, and much time 35 is saved by reason of the more rapid progress of the train over the railroad right of way as compared with the progress over any highway connecting the same points. Any number of highway vehicles may be incorporated in a train, with 40 in reasonable limits, and a great advantage of the improved method resides in the fact that these highway units may vary greatly in size, shape, length, and width without rendering it in the least inconvenient to assemble the train at 45 any point of highway or roadway interchange or to disassemble the train at its destination. All that is required of a highway unit is that it be provided at each end with coupling units suitable for engagement with the coupling units mounted 50 upon the rail vehicles.

Having thus described the invention, what is claimed as new and desired to be secured by Letters Patent is:

1. The method of transporting goods from a 55 shipment point to a distant destination by the use of highways and railways and highway and railway rolling stock which comprises, packing the goods at a shipment point in the body of a vehicle equipped with wheels for highway travel, moving said vehicle over a highway to a point 60 of railway interchange, detachably mounting the ends of the body of said vehicle directly upon two disconnected spaced railway trucks equipped with rail wheels, the road wheels of said vehicle being suspended and wholly inoperative while 65 said vehicle is so supported, moving said trucks and the vehicle supported thereby along the railway to the point of highway interchange nearest the ultimate destination of said vehicle, removing 70 said vehicle from its supporting railway trucks and placing the same upon a highway, and moving the vehicle while supported by its own wheels over a highway to its destination.

2. The method of transporting goods from a 75 point of shipment to a distant destination by the

use of highways and railways and highway and railway rolling stock which comprises, packing the goods at a shipment point in the body of a vehicle equipped with wheels for highway travel, detachably mounting the ends of the body of said vehicle directly upon two disconnected spaced railway trucks equipped with rail wheels, the road wheels of said vehicle being suspended and wholly inoperative while said vehicle is so supported, moving said trucks and the vehicle supported thereby along the trackway to the point of highway interchange nearest the ultimate destination of said vehicle, removing said vehicle from its supporting trucks and placing the same upon a highway, and moving the vehicle while supported by its own wheels over a highway to its destination. 10 15

3. The method of transporting goods from a shipping point to a distant destination by the use of highways and railways and highway and railway rolling stock which comprises, packing the goods at a shipment point in the body of a vehicle equipped with wheels for highway travel, moving said vehicle over a highway to a point of railway interchange, detachably mounting the 20 ends of the body of said vehicle directly upon two spaced disconnected railway trucks equipped with rail wheels, the road wheels of said vehicle being suspended and wholly inoperative while said vehicle is so supported, and moving said trucks 25 and vehicle supported thereby along the railway.

4. The method of transporting goods which comprises placing the goods in the body of a road vehicle, bodily elevating the vehicle and maintaining it in elevated position by mounting 30 the ends thereof, respectively, directly upon two spaced disconnected railway trucks, applying tractive effort to one of the trucks, which effort is communicated to the other truck through the vehicle, whereby both trucks and vehicle are 35 moved as a unit to the desired destination, and removing the trucks from beneath the vehicle and bodily lowering the same until it rests upon its 40 own supporting means.

5. The method of transporting goods over rail- 45 ways which includes the steps: first, placing the goods in bodies equipped with road wheels; second, mounting the ends of each body directly upon two spaced disconnected railway trucks positioned upon a single track, each such truck, 50 except those at the ends of the line, supporting the adjacent ends of two adjacent bodies, whereby a continuous train of alternately arranged trucks and bodies is formed; and applying tractive effort to one of the end trucks to move the 55 train, the tractive effort being transmitted through the bodies of the trucks.

6. In a railway train, in combination, two spaced railway vehicles, a road vehicle having road wheels wholly supported by said railway 60 vehicles, the ends of the body portion of the road vehicle being pivotally and demountably secured to said rail vehicles, and the highway wheels of the road vehicle being suspended intermediate the rail vehicles. 65

7. A railway train comprising alternately arranged road and rail vehicles, each rail vehicle comprising the sole draft connection between adjacent road vehicles, and the road vehicles being detachably mounted and raised upon the rail 70 vehicles so that their road wheels are in raised and inoperative position, each rail vehicle being provided with an outwardly and downwardly inclined member at each end comprising a slide 75 down which the end of the adjacent road vehicle

moves when relative longitudinal movement of separation occurs, whereby the road wheels of the road vehicle are rendered operative.

- 5 8. A railway train comprising alternately ar-
ranged road and rail vehicles, each rail vehicle comprising the sole draft connection between ad-
jacent road vehicles, a king pin projecting down-
wardly from each end of each road vehicle, a
10 member mounted upon each end of each rail
vehicle for supporting the superposed end of a
road vehicle, each such means being centrally
apertured for the reception of the king pin of a
road vehicle, and means for releasably locking
said king pins in said recesses.

- 15 9. A railway train comprising alternately ar-

ranged road and rail vehicles, the road vehicles being provided with road engaging means and being demountably supported upon the rail vehicles and each rail vehicle constituting the sole draft connection between adjacent road 5 vehicles.

10. A railway train comprising alternately ar-
ranged road and rail vehicles detachably con-
nected together, the road vehicle being provided
with road engaging means and having their ends 10
pivotally and detachably secured to adjacent rail
vehicles and being otherwise unsupported, and
the rail vehicles constituting the sole draft con-
nections between pairs of adjacent road vehicles.

CHARLES A. NELSON. 15
